REFRIGERATING APPARATUS

Lawrence A. Philipp, Detroit, Mich., assignor, by
mesne assignments, to Nash-Kelvinator Cor-
poration, Detroit, Mich., a corporation of Mary-
land

Original application April 5, 1933, Serial No.
664,523. Divided and this application March
11, 1935, Serial No. 10,487

1 Claim. (Cl. 62—126)

This invention relates to refrigerating apparatus, and more particularly to refrigerating systems of the flooded type.

5 This application is a division of my copending application, Serial No. 664,523, filed April 5, 1933, for Refrigerating apparatus, and issued as Patent No. 2,021,924, Nov. 26, 1935.

10 One of the objects of my invention is to provide a refrigerating system of the type including a condensing element and a flooded evaporating element with a refrigerant accumulator, which serves at all times to prevent the flow of liquid refrigerant from the evaporating element to the condensing element.

15 Another object of my invention is to provide a refrigerating system of the type including a condensing element and a flooded evaporating element with a refrigerant accumulator of sufficient size to permit variations in the charge of refrigerant admitted to the system without the possibilities of circulating liquid refrigerant from the evaporating element to the condensing element.

20 Another object of my invention is to provide a refrigerating system of the type including a condensing element, evaporating element, and a high side float mechanism, with a refrigerant accumulator at the outlet of said evaporating element, which accumulator is of sufficient size to accommodate any liquid refrigerant which may be circulated through the evaporating element either during normal operation of the system or all of the liquid refrigerant contained in the system which may be circulated through the evaporating element in the event said float mechanism becomes faulty in operation, or any other condition causing abnormal operation of said system, to thereby provide for refrigeration throughout the entire surface of the evaporating element by insuring delivery of liquid refrigerant through 25 said evaporating element to the outlet end thereof without the possibility of passing liquid refrigerant into said condensing element.

30 Other objects and advantages will be apparent from the following description reference being had to the accompanying drawing.

45 In the drawing:

Fig. 1 is a front view in elevation of a refrigerant evaporating element embodying features of my invention.

50 Fig. 2 is a rear view in elevation of the evaporating element shown in Fig. 5;

Fig. 3 is an enlarged side view in elevation, partly broken away, of the evaporating element shown in Figs. 1 and 2, and showing diagrammatically a refrigerant condensing element; and

Fig. 4 is a view in cross section of a refrigerant accumulator embodying features of my invention.

Referring to the drawing, a refrigerant evaporating element 22 is shown to which is operatively connected a refrigerant condensing element 24.

5 The evaporating element 22 comprises, in general, a sleeve 26 arranged for receiving a plurality of ice making receptacles (not shown). A refrigerant expansion coil 28 is sinuously wound 10 around three sides of the sleeve 26. Liquid refrigerant is supplied to the refrigerant evaporator 28 through a liquid supply conduit 30. An elongated refrigerant accumulator 32 is horizontally disposed along the top wall of the sleeve 26. 15 An outlet portion 36 of the coil 28 is connected to the accumulator 32.

The refrigerant condensing element 24 comprises, in general, a compressor 42, motor 43 for operating the compressor, condenser 45, and a combination liquid refrigerant receiver and high side float mechanism 46. The compressor withdraws evaporated refrigerant from the element 22 through a vapor return conduit 48, compresses the gaseous refrigerant and delivers it to the condenser, wherein it is liquefied and from which it is delivered into the housing of the receiver-float valve mechanism. Liquid refrigerant is delivered to the element 22 through the liquid conduit 30 under the control of the float mechanism 46.

25 In the refrigerating system hereinbefore described, I provide a charge of liquid refrigerant which is sufficient to permit the delivery of liquid refrigerant through the coil 28 and to the outlet end 36 of coil 28 during normal operation of the 30 system. Thus, refrigeration is insured throughout the entire length of coil 28.

35 In order to prevent the slop-over of liquid refrigerant from the outlet 36 of coil 28 into the vapor return conduit 48, I have provided the refrigerant accumulator 32. Thus, it will be noted that any variations in the charge of liquid refrigerant admitted to the system is immaterial, since it would be necessary to rise in the accumulator to a point above the outlet 36 before 40 the liquid would be delivered to the vapor conduit. Thus, it will be noted that the accumulator takes care of variations in the charge of refrigerant introduced into the system.

45 In order to prevent the slop-over of liquid refrigerant into the vapor conduit during any abnormal operation of the system, such, for example, as a leaky float valve mechanism, I have constructed the accumulator of sufficient size as 50 to accommodate all of the liquid refrigerant in 55

the system which is not contained in the coil 28. Thus, the possibility of frost back of the vapor conduit or destruction to parts of the compressor is eliminated, since no liquid refrigerant passes into the vapor conduit 48. Another form of abnormal operation of the system may include the continuous insertion of warm substances in the evaporator to be frozen. When this occurs, the system operates more than normal and evaporation takes place in coil 28 much faster than normally, thus causing more liquid to pass through said coil. In a system of the type herein disclosed, it is usual to place the outlet of the combination liquid refrigerant receiver at the lowermost part thereof. Thus, any leakage of the float valve mechanism results in passage of all of the liquid in said receiver into the coil 28. Thus, an accumulator of sufficient size to accommodate all of the liquid in the system not contained in the coil 28 readily serves at all times to prevent the flow of liquid into the condensing element or conduit 48. Preferably, the accumulator is disposed on the upper surface of element 22.

Preferably, the system is intermittently operated. In order to control the operation of the system, I provide an automatic switch 70 which controls the motor circuit to the power mains 71. Preferably, the switch is thermostatically controlled by means of a thermostatic fluid containing bulb 73, which is disposed in metallic contact with the fitting 81, which is disposed in thermal contact with the top wall of sleeve 26 and partially in the path of the circulating air in the cabinet in which the evaporator is located.

In order to prevent refrigeration taking place immediately upon entrance of the liquid refrigerant into the supply conduit 30 after leaving the float mechanism 46, I have provided a pres-

sure responsive valve 85. This valve interconnects conduit 30 and coil 28. The valve 85 maintains the pressures in the supply conduit 30 sufficiently high enough to prevent refrigeration in conduit 30 to the extent of collection of frost thereon. This prevents loss of refrigeration and increases the capacity of the apparatus. Any suitable pressure responsive valve may be used for this purpose such, for example, as a weighted valve proper (not shown) responsive to changes in pressures in conduit 30.

Although only a preferred form of the invention has been illustrated, and that form described in detail, it will be apparent to those skilled in the art that various modifications may be made therein without departing from the spirit of the invention or from the scope of the appended claim.

What I claim is:

Refrigerating apparatus, comprising a refrigerant evaporating element of the flooded type including a box-like sleeve providing a freezing zone, a refrigerant evaporating conduit in the form of a serpentine coil associated with three sides of said sleeve for freezing substances in said zone and for cooling circulating air exteriorly of said zone, a longitudinally extending refrigerant vessel extending along the top wall of said sleeve, means for introducing liquid refrigerant into one end of said serpentine coil and causing same to flow in one direction only, to the terminating end thereof in said vessel and for withdrawing vaporized refrigerant from the gas space in said vessel and means responsive to changes in temperatures in said sleeve for controlling said latter means.

LAWRENCE A. PHILIPP.
